CONCRETE ROUGH BOX FOR BURIAL PURPOSES

Fred Knuth, Council Bluffs, Iowa

Application December 8, 1934, Serial No. 756,697

3 Claims. (Cl. 72—7)

The invention relates to a concrete rough box for burial purposes.

The object of the present invention is to provide a simple, practical, and durable concrete rough box for burial purposes adapted to be constructed in sections to enable it to be easily handled and capable of being readily and securely set up for use in a grave in position to receive a casket.

10. A further object of the invention is to provide a sectional concrete rough box of this character adapted to permit a casket to be lowered into it by straps or the like in the usual manner and provided at the bottom with means located 15 at the ends and central portion of the same for supporting the casket in a slightly elevated position above the bottom of the rough box to permit the straps employed for lowering the casket into the rough box to be readily slipped out after 20 the casket has been lowered into the rough box.

It is also an object of the invention to provide a concrete rough box for burial purposes equipped with a top composed of sections adapted to be readily placed in position over the body of 25 the rough box after a casket has been lowered into the same.

With these and other objects in view, the invention consists in the construction and novel combination and arrangement of parts herein- 30 after fully described, illustrated in the accompanying drawing and pointed out in the claims hereto appended, it being understood that various changes in the form, proportion and minor de- 35 tails of construction, within the scope of the claims, may be resorted to without departing from the spirit or sacrificing any of the advantages of the invention.

In the drawing:—

40. Figure 1 is a perspective view of a portion of the body of a sectional concrete rough box constructed in accordance with this invention, the cover being removed to illustrate the corner and side connecting elements of the sides and ends.

Fig. 2 is a horizontal sectional view of the concrete rough box.

Fig. 3 is a longitudinal sectional view of the same.

Fig. 4 is a vertical sectional view taken substantially on the line 4—4 of Fig. 3, illustrating the arrangement of the dowel pins for securing the sides to the bottom of the concrete rough box.

50. In the accompanying drawing in which is illustrated the preferred embodiment of the invention the concrete rough box which is designed to be made in standard sizes when made in the larger

5 sizes comprises in its construction a bottom, top and sides composed of sections and ends each consisting of a single slab or section. The bottom is composed of sections 1 and 2; the sides are composed of sections 3 and 4 and the top is composed of sections 5 and 6. The ends 7 which are arranged upon the outer end portions of the sections 1 and 2 of the bottom of the rough box are of a width slightly less than the bottom sections 1 and 2 and are located between the outer end 10 portions of the sections 3 and 4 of the sides which are also arranged upon the bottom of the concrete rough box. The sections of the top, bottom and sides of the concrete rough box and the ends thereof consist of molded concrete slabs 15 reinforced with six inch wire mesh 8, preferably of No. 9 wire but the size of the mesh and the wire may of course be varied and in practice the slabs or sections of the body portion of the rough box will preferably be one inch in thickness and the sections of the top one and one-half inches thick but the thickness of the slabs or sections may be varied as desired.

20. The sections 1 and 2 of the bottom of the rough box are provided at the upper faces of their end 25 portions with integral molded cleats 9 preferably tapered inwardly, as clearly illustrated in Fig. 2 of the drawing, and presenting straight transverse outer edges 10 which form abutments for the lower portions of the ends of the rough box. 30 The sections 1 and 2 of the bottom of the rough box have an overlapping joint formed by an integral molded transverse cleat 11 upwardly offset from the plane of the upper faces of the sections 1 and 2 of the bottom and extending longitudinally from the section 2 and arranged in overlapping relation with the inner end of the section 1 and forming a recess for the reception 35 of the inner end portion of the said section 1. The middle cleat 11 is of the same thickness as 40 the end cleats 9 and the said cleats 9 and 11 are arranged to support a casket in a slightly elevated position above the bottom sections 1 and 2 of the rough box to permit the straps employed for lowering a casket into a grave and the rough 45 box to slip readily out from under the casket.

The sections 5 and 6 of the top of the rough box are provided with suitable handles 12 and have an overlapping joint consisting of a cleat or extension 13 molded integral with the section 50 6 and upwardly offset from the plane of the upper face of the section 5 to provide a recess 14 to receive the inner end portion of the section 5 similar to the recess 15 formed by the middle cleat 11 of the section 2 of the bottom of the rough 55

box. The top of the rough box is of a size to extend over and rest upon the upper edges of the sides and ends of the rough box.

The sectional concrete rough box is adapted to be readily assembled in a grave by first arranging the sections 1 and 2 of the bottom of the rough box upon the bottom of the grave. The ends are placed in an upright position upon the outer end portions of the sections 1 and 2 and the sections 3 and 4 of the sides are arranged upon the side portions of the sections 1 and 2 of the bottom and extend to the outer end edges thereof and receive the ends 1 of the rough box between them. In order to support the side walls of the rough box in position until the casket is lowered into the same and the top sections placed on the body portion of the rough box the sides are provided with dowel pins 16 arranged vertically and having their upper portions molded in the sections 3 and 4 at the lower edges thereof and having projecting lower portions 17 which extend into vertical holes 18 in the sections 1 and 2 of the bottom of the rough box. When the dowel pins 16 are fitted in the holes of the bottom of the rough box the sides thereof will be interlocked with the bottom of the rough box and the said dowel pins will assist in maintaining the sides in a vertical position.

The sides and ends of the rough box are also connected at the corners of the rough box by angle connecting members 19 and the sections 3 and 4 of the sides of the rough box are connected at their adjacent ends by intermediate connecting members 20. The corner connecting members 19 are substantially L-shaped and are provided at their terminals with depending pins 21 which are fitted in sockets 22 formed in the sides and ends of the rough box at the upper edges thereof adjacent the corners of the same. The L-shaped body portion of the corner connecting members 19 is arranged horizontally and rests upon the upper edges of the sides and ends as clearly illustrated in Fig. 1 of the drawing. The intermediate connecting members 20 are substantially U-shaped and consist of a straight body portion and depending pins 23 which fit in sockets 24 formed in the inner end portions of the sections 3 and 4 of the rough box at the upper edges thereof. The straight body portion of the intermediate connecting members rests upon the upper edges of the sections 3 and 4 of the sides of the rough box as clearly shown in Fig. 1 of the drawing. When the bottom dowel pins are fitted in the holes in the bottom of the rough box and the connecting members 19 and 20 are placed in the sockets of the upper edges of the sides and ends the latter are securely held in assembled relation to form with the bottom the body portion of the rough box. The handles 12 will enable the sections of the top of the rough box to be readily placed on the body thereof after a casket has been lowered into a grave and into the concrete rough box.

In the manufacture of rough boxes of the smaller sizes the top, sides and bottom may each consist of a single slab. While the rough box is designed to be molded of concrete any other suitable plastic material having the characteristics of artificial stone may of course be employed.

What is claimed is:—

1. A rough box for burial purposes consisting of bottom, side and end slabs of molded plastic material adapted to be assembled in a grave and provided with means for interlocking the slabs with one another, the bottom slabs of the rough box being provided at their ends with integral molded enlargements forming cleats adapted to support the ends of a casket in an elevated position above the bottom of the rough box to permit casket lowering straps to slip readily from beneath a casket after same has been lowered into the rough box, said cleats being also provided with straight outer transverse edges spaced from the ends of the bottom slabs and forming abutments for the end slabs of the rough box and the end edges of the cleats being spaced from the sides of the bottom slabs and forming abutments for the side slabs of the rough box.

2. A rough box for burial purposes consisting of bottom, side and end slabs of molded plastic material adapted to be assembled in a grave and provided with means for interlocking the slabs with one another, the bottom of the rough box being composed of two sections provided at their upper faces with end and intermediate cleats molded integral with the sections of the bottom and cooperating to support the ends and central portion of a casket in a slightly elevated position above the bottom of the rough box and the middle cleat being an offset of, and extending from, one of the sections of the bottom and arranged in overlapping relation with the other section of the bottom to form an overlapping joint between the sections.

3. A rough box for burial purposes consisting of bottom, side and end slabs of molded plastic material adapted to be assembled in a grave and provided with means for interlocking the slabs with one another, the bottom of the rough box being composed of two sections provided at their upper faces with end and intermediate cleats molded integral with the sections of the bottom and cooperating to support the ends and central portion of a casket in a slightly elevated position above the bottom of the rough box and the middle cleat being an upwardly offset extension of one of the sections of the bottom and arranged in overlapping relation with the other section of the bottom to form an overlapping joint between the sections, the end edges of the end and intermediate cleats forming abutments for the sides of the rough box and the end cleats having straight transverse faces forming abutments for the ends of the rough box.

FRED KNUTH.
